UNITED STATES PATENT OFFICE.

THOMAS GEORGE STILES, OF ARLINGTON, NEW JERSEY.

CIRCUIT-CONTROLLER.

1,030,622.

Specification of Letters Patent. Patented June 25, 1912.

Application filed May 25, 1910. Serial No. 563,269.

To all whom it may concern:

Be it known that I, THOMAS GEORGE STILES, a citizen of the United States, and a resident of Arlington, in the county of Essex and State of New Jersey, have invented certain new and useful Improvements in Circuit-Controllers, of which the following is a specification.

This invention relates to improvements in circuit controllers, especially draw-bridge circuit controllers, and the main object of the invention is to provide an improved controller of the sliding or plug-contact type, and especially of the multiple plug-contact type, so constructed as to provide on the coöperative or contacting members a large number of points in close and firm engagement to assure the proper passage of current through these contacting members when they are in engagement.

In carrying the invention into effect I prefer to employ as the principal current-conducting elements of the circuit-controller a spring contact of the sliding-plug type and a conducting socket in sliding contact with said spring contact when the circuit through these parts is closed. This spring contact is preferably so constructed as to be put under compression by the walls of the socket when it enters said socket and make contact with such walls at opposite edges of each element or spring-finger of the spring contact, in order that good contact paths may be provided for the passage of the current through the circuit controller.

For draw-bridge work the coöperative plugs, and sockets, organized to make proper sliding engagement in pairs will be provided in multiple, a plurality of like sockets being preferably carried by the abutment member of the circuit-controller and a multiplicity of like plugs or spring contacts being provided on the draw-bridge member of the circuit-controller. In such a multiple circuit-controller I prefer to mount all of the plugs or spring contacts on a sliding frame carried by the draw-bridge member and to slide this frame back and forth to carry each sliding or plug element of the circuit-controller into or out of engagement with the walls of its socket to make or break its circuit, as the case may be.

Other features of my invention relate to the provision in connection with this sliding

frame carrying the plug elements of the circuit-controller, of a casing member or members, preferably top, bottom and side covers, for inclosing by a telescoping action the operative parts of the abutment member of the circuit-controller when the plugs and sockets are in engagement and thus protecting the circuit-controller from the action of the elements.

A further important feature of the invention is the provision as one of the main parts of each sliding element of the circuit-controller, of a long contact-rod, preferably angular in cross section, which slides through a fixed spring contact comprising a circuit of contact-springs or fingers each of which maintains electrical connection with such contact-rod whatever the position of the latter may be, and preferably is in constant sliding engagement with a sharp edge or angle of such rod. This construction assures proper electrical connection to each plug element of the circuit-controller in whatever position the sliding plug may be.

Other features of the invention not hereinbefore described will be hereinafter referred to and are illustrated in the accompanying drawings, in which—

Figure 1 is a plan, with parts broken away, of the bridge member of a multiple drawbridge circuit-controller embodying my invention; Fig. 2 is a horizontal section, the section being taken in the line A—A, Fig. 4, of the coöperating or abutment member of said circuit-controller placed in operative relation with the complementary member shown in Fig. 1; Fig. 3 is a vertical section of the drawbridge member of the circuit-controller, the section being taken in the line B—B, Fig. 1; Fig. 4 is a vertical section of the abutment member of said circuit-controller, the section being taken in line C—C, Fig. 2; Fig. 5 is an enlarged detail illustrating in cross section a single element of the circuit-controller with the spring fingers of the plug switch in contact with the walls of its socket element; Fig. 6 is a plan, with parts broken away, of a draw-bridge circuit-controller illustrating a modification of the invention. Fig. 7 is a vertical section of the same, the section being taken in the line D—D, Fig. 6. Fig. 8 is a detail illustrating in side elevation with parts broken away the plug-switch shown in

Fig. 5, and Fig. 9 is a detail illustrating in cross-section a spring contact device through which a contact rod slides.

Similar characters designate like parts in all the figures of the drawings.

Referring first to Figs. 1 to 5 inclusive, 1 designates the main frame element of the draw-bridge member of the circuit-controller, this being in the construction shown 10 a substantially rectangular box having side walls, a rear end wall and a bottom, but open at the front to permit sliding movement of a frame carrying the sliding contact elements of the controller. This main 15 frame member or box may be fastened to a drawbridge in any suitable manner, as by means of bolts passing through ears 2 projecting from the bottom of the box. At the opposite ends of the inner sides of this box 20 or casing 1, anti-friction rollers, such as 3, are carried, these being located near the top of the box 1 and constituting supports for a sliding cover member, which may be of the type indicated at 4. This cover has 25 depending flanges, such as 5, at the sides and rear end thereof, which extend down over the outside of the upper edges of the box member 1, to keep out rain, snow, etc. Near its forward end the cover 4 has depending 30 side covers, such as 6, extending almost to the bottom of the box 1, these also serving to protect the working parts of the controller from the weather, especially at the point of connection of the bridge and abutment members. All of the sliding parts of 35 the circuit-controller are carried in this case by the drawbridge member, and all of them are preferably supported for movement in unison with the cover 4. In order to mount 40 and operate the sliding elements of the circuit-controller properly, a slide-frame is provided which is suspended at one end from the cover 4 and suitably supported and guided at its opposite end. This frame 45 as shown comprises a cross-head 7, a slide-block 8 to which the cross-head 7 is secured and which is mounted on a suitable slide 9 carried on guides, such as 10 and 11, at opposite ends of the box 1, and a coacting bar 50 12 by means of which the circuit-controller is operated when the draw-bridge with which it coacts is opened or closed. The cross-head 7 constitutes in this construction a support for the rear ends of a multiplicity 55 of contact-rods each one of which is insulated from every other. Each rod is preferably angular in cross section, the construction illustrated being rectangular rods, which are designated respectively by 13. At 60 its rear end each rod is reduced where it passes through the cross-head 7 and is insulated from the cross-head by an insulating bushing, such as 14, suitable means, preferably a nut on the threaded rear end 65 of each rod being employed for securing the rod firmly to the cross-head. At its forward end each of these rods 13 passes through and is guided in a cross-board 14' fastened to the bottom of the main frame or box 1. This cross-board constitutes 70 merely a supporting guide for the contact-rods 13 and is not fastened thereto. Each of said rods preferably works in an insulated bushing, such as 15, mounted in said cross-board, and each of these bushings also 75 preferably carries a spring contact device also insulated from the cross-board. Each of these contact devices is designated generally by 16 and consists of a plurality or circuit of contact springs or fingers, 80 preferably bowed, and each attached at one end to the adjacent bushing and each in sliding engagement at its free end with the contact-rod. These spring fingers are so placed that they engage preferably the edges of the rod 85 instead of the flat faces thereof, thereby assuring good contact. Each of these bushings also carries the insulated binding-posts, such as 17, from which conductors, such as 18, pass to terminals 19 on a terminal-board 90 20. Two terminal-boards are shown at opposite sides of the box, one half of the connections being made to one board and the other half to the opposite board. All the sliding parts just described move back and forth in the box 1 with the contact-rods 95 sliding through their guiding bushings in the cross-board 14' and moving with the cover 4 and other parts as before described, practically as a unit. For further strength, 10 a brace 21 extends from the cross-head centrally of the cover 4 and is bolted to the underside of said cover as well as to the upper side of the cross-head. The sliding element 11 so constituted moves freely on the anti-friction rollers 3 and is practically suspended therefrom and requires no other support save that for the movable forward ends of the contact-rods, which support is furnished, as before described, by the cross-board 14'. 12 At their extreme forward ends the contact-rods 13 carry plug-contacts, preferably spring contacts, for engagement with the complementary circuit-controlling members, to wit, the sockets before referred to carried by the abutment member. These plugs or spring contacts are designated generally by 22. Each preferably consists of a plurality or circuit of spring arms or fingers, 13 here shown as four in number, and formed from two pieces of spring metal, secured at their inner ends to the flat faces of the contact-rods, and having at their outer ends punched circular openings through which the rounded turned-down end of the contact-rod passes, the fingers being secured in place at their outer ends by a screw passing into the end of the rod and formed with a pointed head. Means are preferably pro- 14

vided for adjustably securing these spring fingers, which are designated by 23, to the flat faces of the contact-rods. As illustrated herein there are four of these fingers 5 for each spring contact, and each finger is adapted to engage at its opposite edges the metal wall of its complementary element or socket member, as clearly illustrated in Fig. 5, from which it will be seen that with four 10 spring fingers there are eight points of contact, making eight paths for the passage of current. In addition to this, it will be noted that when each spring plug is forced into the complementary socket the spring fingers 15 thereof are placed under considerable tension, thereby assuring good contact with the walls of the socket, and at the same time giving great stiffness to the plug contact considered as a whole. At their inner ends 20 these spring-fingers are slotted as shown at 23' to receive the shanks of screws 23'', by means of which said fingers and the respective rods 13 are joined by screw and slot connections. These loose connections 25 between the inner ends of said contact arms and their respective rod 13 while permitting the proper compression of said contacts permit sufficient movement to prevent breakage of the contact arms. Each of the spring 30 contacts 22 and each contact-rod 13 is preferably made of bronze and co-operates with a brass socket member.

For each sliding plug just described a complementary contact element is provided 35 on the abutment member of the circuit-controller, as is clearly illustrated in Figs. 2 and 4. These complementary elements are preferably brass sockets or tubes, such as 24, which in this case are insulated from one 40 another, they being shown as mounted in fiber tubes 25, the inner ends of which are supported in the front plate 26 of a box 27 constituting the main frame member or casing of the abutment member of the circuit- 45 controller; while the rear ends of the brass tubes are closed and have secured thereto insulated binding-posts 28 the main element or post of each of which passes through an insulating bushing 29. The rear ends of all 50 of these fiber tubes are mounted in a cross-plate 30, and each horizontal row of insulating bushings 29 is mounted as shown in Fig. 2 in a cross-strip, such as 31, bolted at its ends to the cross-plate 30. The end of 55 the box 27 adjacent to the binding-posts 28 is closed by a swinging door 32, which may be secured to the top of the box by means of the devices shown at 33 and locked in that position, as by means of a padlock (not 60 shown), in a similar manner to that illustrated at 34 in Fig. 1 or locking similar doors forming parts of the casing 1. The abutment box 27 also has means, such as lugs 35, for fastening it to the abutment of 65 the bridge in substantially the same way

that the box 1 is fastened to the bridge member. The various conductors leading to the binding-posts 28 are united in a cable at the land end of the circuit-controller, which cable passes through and fits 70 closely in the opening 36 in the casing 27.

From the foregoing description it will be seen that when the sliding member of the circuit-controller is moved the proper distance to the right, as seen in Figs. 1 and 3, 75 the plugs or spring contacts 22 will enter the sockets 24 and simultaneously close all of the circuits of the controller, sliding contact being at the same time maintained between the rods 13 and the terminal boards 80 by the spring contacts 16 connected with such boards. At the same time the movable cover and sides of the bridge member of the controller, together with the movable bottom slide 9, will move with the plugs to a 85 point where they will completely inclose the adjacent portions of the top and sides of the casing member 27 and also cover the conducting sockets from beneath, this being due to the fact that the slide 9 moves to 90 a point where it strikes the stop 37, thus completely boxing in and inclosing the co-operative contact elements on all sides, making a multiple drawbridge circuit controller that is practically weatherproof and yet can 95 be opened by a single movement.

In Figs. 6 and 7 I have illustrated a modification of the invention with the circuit-controller closed, instead of open, as in the other views. In addition to this the contact 100 devices on the drawbridge member of the controller are considerably modified. Here the contact-rods 13 do not pass near their free ends through stationary spring contacts, but instead each rod 13 has secured thereto a spring contact 38 similar to that shown at 16 in Figs. 1 and 3, and this contact 38 is in sliding engagement with the walls of tubes 39 similar to those shown at 24 and similarly mounted in fiber cylinders 105 or bushings 40. These tubes 39 and 40 are fixed relatively to the box or casing 1. The circuits of the different elements of the bridge member are made through conductors 110 41 connected with the closed ends of the metal tubes 39 and with the respective terminals 19 of the terminal-board. Thus the spring contacts 38 are always in sliding contact with the tubes 39, and through these parts electrical connection is maintained between the contact-rods 13 and the terminal-boards 20. In other respects the construction of the circuit-controller shown in Figs. 115 6 and 7 is substantially the same as that of the one shown in the other views, except for some changes in the proportions of parts. Corresponding parts of the circuit-controller illustrated in these views are designated by the same reference characters as in the preceding views.

What I claim is:

1. In a sliding circuit controller, the combination with a contact-rod angular in cross section, of a coöperating spring contact comprising contact-fingers making sliding contact with the edges of said rod.
2. In a sliding circuit controller, the combination with a contact-rod rectangular in cross section, of a coöperating spring contact through which said rod slides, said contact comprising four contact fingers each in sliding contact with one of the edges of said rod.
3. In a sliding circuit controller, the combination with a contact-socket, of a sliding contact-rod, and a spring contact angular in cross-section secured to said rod and slideable into and out of said socket and comprising a plurality of contact fingers each outwardly bowed substantially throughout its length in a direction lengthwise of the contact-rod and supported at both ends by said contact-rod and adapted to make contact at its angular edges only with said socket.
4. In a sliding circuit controller, the combination with a tubular contact-socket, of a sliding contact-rod, and a spring contact angular in cross-section secured to said rod and slideable into and out of said socket and comprising a plurality of contact-fingers each outwardly bowed lengthwise of the contact-rod and making contact at its opposite edges only with the tubular socket.
5. In a sliding circuit controller, the combination with a contact-socket, of a sliding contact-rod, a spring contact angular in cross-section secured to said rod and slideable into and out of said socket and comprising a plurality of contact-fingers adapted to make contact at their angular edges only with said socket, and a contact device with which said contact-rod is in constant sliding engagement.
6. In a sliding circuit controller, the combination with a contact-socket, of a sliding contact-rod, a spring contact angular in cross-section secured to said rod and slideable into and out of said socket and comprising a plurality of contact-fingers adapted to make contact at their angular edges only with said socket, and a spring contact device with which said contact-rod is in constant sliding engagement.
7. In a sliding circuit controller, the combination with a contact-socket, of a sliding contact-rod, a spring contact angular in cross-section secured to said rod and slideable into and out of said socket and comprising a plurality of contact-fingers adapted to make contact at their angular edges only with said socket, and a spring contact comprising a circuit of contact-fingers making constant sliding engagement with said rod.
8. In a sliding circuit controller, the combination with a contact-socket and with a binding-post coöperative therewith, of a sliding contact-rod, a spring contact angular in cross-section secured to said rod and slideable into and out of said socket and adapted to make contact at its angular edges only with said socket, and a combined fixed spring contact and binding-post coöperative with said contact-rod and through which fixed spring contact said rod is adapted to slide.
9. In a sliding circuit controller, the combination with a contact-socket and with a binding-post coöperative therewith, of a sliding contact-rod, a spring contact angular in cross-section secured to said rod and slideable into and out of said socket and adapted to make contact at its angular edges only with said socket, and a combined fixed bearing, binding-post and spring contact, all coöperative with said contact-rod and through which bearing and spring contact said rod is adapted to slide in contact with the walls of said bearing.
10. A draw-bridge circuit controller, comprising draw-bridge and abutment members, one of which has aligned multiple tubular insulated contact-sockets, and the other of which has multiple insulated contact-rods slideable into and out of said sockets in alignment therewith, each rod carrying a spring contact angular in cross section and comprising a plurality of contact-fingers adapted to make contact at their angular edges only with their contact-socket, and a supporting guide for each of said rods.
11. A draw-bridge circuit controller, comprising draw-bridge and abutment members, one of which has multiple tubular insulated contact-sockets, and the other of which has multiple insulated contact-rods angular in cross section and slideable into and out of said sockets, each rod carrying a spring contact comprising a plurality of contact-fingers each secured at one of its ends to said contact-rod and each resting at its free end against one of said flat faces and each outwardly bowed lengthwise of the contact-rod and adapted to be put under compression when said spring contact enters said socket.
12. A draw-bridge circuit controller, comprising draw-bridge and abutment members constructed to telescope one into the other, one of said members having multiple insulated contact-sockets, and the other of said members comprising fixed and sliding frames, the sliding frame having multiple insulated contact-rods slideable into and out of said sockets, each rod carrying a spring contact device angular in cross-section and adapted to make contact at its angular edges only with its respective contact-socket.
13. A draw-bridge circuit controller, comprising draw-bridge and abutment mem-

bers constructed to telescope one into the other, one of said members having multiple insulated contact-sockets and the other of said members comprising fixed and sliding frames, the sliding frame having multiple insulated contact-rods angular in cross-section and slidable into and out of said sockets, each rod carrying a spring contact device, and multiple insulated spring contacts 10 through which the respective contact-rods pass and with which said rods are in constant sliding engagement but at their edges only.

14. A draw-bridge circuit controller, comprising draw-bridge and abutment members constructed to telescope one into the other, one of said members having multiple insulated contact-sockets, and the other of said members having multiple insulated contact-rods angular in cross-section and slid- 20 able into and out of said sockets, each rod carrying a spring contact device, and multiple insulated spring contacts and bearings through which the respective contact-rods 25 pass and with which said rods are in constant sliding engagement but at their edges only.

15. A draw-bridge circuit controller, comprising draw-bridge and abutment members, one of which has multiple tubular insulated contact-sockets and the other of which has a sliding cover adapted to slide over and telescope with said first member of the draw-bridge controller, said sliding cover carrying 35 multiple insulated contact-rods slidable

into and out of said sockets, each rod carrying a contact device coöperative with said socket.

16. A draw-bridge circuit controller, comprising draw-bridge and abutment members, one of which has multiple tubular insulated contact-sockets and the other of which has top, side and bottom covers adapted to slide in unison and telescope with said first draw-bridge member, said sliding covers carrying 40 multiple insulated contact-rods slidable into and out of said sockets, each rod carrying a contact device coöperative with said socket.

17. A draw-bridge circuit controller, comprising draw-bridge and abutment members, one of which has multiple insulated contact-sockets, and the other of which has multiple insulated contact-rods slidable into and out of said sockets, each rod carrying a spring contact device angular in cross-section and adapted to make contact at its angular edges only with its respective socket, multiple insulated spring contacts and binding-posts through which contacts said contact-rods pass and with which said rods are in constant sliding engagement, a terminal board, and conductors connecting said terminal board and binding-posts.

Signed at New York in the county of New York and State of New York this 19 65 day of May, A. D. 1910.

THOMAS GEORGE STILES.
